(57) **CLAIM**

The ornamental design for a stand for tablet PC, as shown and described.

DESCRIPTION

FIG. 1 is a perspective view of a stand for tablet PC, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another perspective view thereof in which a tablet PC is combined with the stand; and,

FIG. 9 is another front view thereof in which a tablet PC is combined with the stand.

The broken lines showing of the tablet PC in FIGS. 8-9 illustrate environment and the remainder of the broken lines in the figures represent unclaimed portions of the stand for tablet PC; the broken lines form no part of the claimed design.
